ENVELOPE-FILLING MACHINE

France E. Guedry, deceased, late of Fort Worth, Tex., by Edith Alderman Guedry, administratrix, Fort Worth, Tex., assignor to Edith Alderman Guedry, Fort Worth, Tex.

Application November 7, 1933, Serial No. 697,044

10 Claims.

(Cl. 93—6)

The present invention relates to improvements in envelope-filling machines.

It is a primary object of the invention to provide an envelope-filling machine which will place 5 circulars or letters in envelopes at a rapid rate and with such accuracy that one and only one of the circulars or letters will be placed in a single envelope.

It is a further object of the invention to provide an envelope-filling machine which will handle 10 envelopes and printed matter of various sizes and weights with little or no adjustment.

It is an object of the invention to provide an envelope-filling machine which is simple in construction, positive in action, which employs but few moving parts, which is not subject to rapid wear, which requires very little power for its operation and which can be manufactured and sold at a low price.

20 Further objects, and objects relating to details and economies of construction and operation will more definitely appear from the detailed description to follow. In one instance, the objects of this invention are obtained by the means described in the following specification. The invention is clearly pointed out in the appended claims. A preferred embodiment of the invention is illustrated in the accompanying drawings, in which:

30 Figure 1 is a view, in side elevation, of a preferred form of envelope-filling machine embodying the invention;

Fig. 2 is a view, in top elevation, of the machine illustrated in Fig. 1;

35 Fig. 3 is a detail sectional view of the envelope magazine, letter magazine, carrier drum and drum-actuated feeding mechanism of the same machine, showing the position of the several elements at the inception of the transfer of a folded letter from the letter magazine to an envelope in the envelope magazine;

40 Fig. 4 is a similar view of the letter magazine and carrier drum at an earlier moment, showing the wiper element of the drum about to engage the lowermost letter in the magazine and cause the latter's initial release therefrom so as to permit engagement of its rear edge by the spring finger or hook of the drum, which hook or finger thereupon effects its transfer from the letter magazine to the envelope;

45 Fig. 5 is a detail sectional view of the drum and letter magazine taken on the line 5—5 of Fig. 4;

50 Fig. 6 is a detail sectional view of the drum, envelope magazine and one of the envelope opening devices, taken on the line 6—6 of Fig. 3;

5 Fig. 7 is a detail view, in perspective, of one of the envelope-opening devices as associated with the engaged portion of the envelope, the portion of the envelope being shown in broken lines;

Fig. 8 is a detail view, in perspective, of the drum mounted hook which conveys the latter or printed circular toward and into the previously spread envelope;

10 Fig. 9 is a more or less diagrammatic view in side elevation, and on a reduced scale, of envelope-flap-opening mechanism applicable to the machine disclosed in Fig. 1 and by the incorporation of which envelopes may be placed in the magazine without the requirement of first unfolding the flaps from the back thereof, the flap-engaging member being shown in initial position;

15 Fig. 10 is a similar view of the same mechanism shown in Fig. 9, the parts being shown in final position with the flap unfolded and lifted; 20 and

Fig. 11 is a view, in top elevation, of the mechanism illustrated in Figs. 9 and 10.

The same reference numerals refer to the same parts throughout the several views.

25 In a broad aspect, the invention relates to envelope-filling machines and is embodied in an apparatus consisting of a rotary drum, a magazine into which folded letters or circulars are charged, a magazine into which envelopes are 30 charged and by which the foremost envelope is held in a plane which is substantially tangent to the cylindrical surface of the drum, mechanism for spreading open the foremost envelope to permit the insertion of a circular or letter, 35 and traversing means carried by the drum which pluck a single letter or card from the magazine therefor and carry said letter or card into inserted relation with the spread and tangentially disposed envelope.

40 More particularly, and with reference to the accompanying drawings, in which there is disclosed what is regarded to constitute a preferred embodiment of the invention, there is provided a base 10 upon which are supported a pair of 45 brackets 11, 12, which constitute the frame of the machine and have bearings in which the shaft 13 of the cylindrical drum 14 is journaled for rotation. A fly wheel 15 having a crank handle 16 is keyed to the shaft 13 and these 50 constitute the means by which smooth and easy rotation of the drum 14 may be effected manually. Bridging the rear portion of the brackets 11, 12 is an upstanding channel member 17 which constitutes the magazine for a supply of folded 55

letters or cards and this member 17 is provided, adjacent its lower edge, with inturned flanges 18 which serve as supporting ledges for the rear edge of the foremost folded letter or card in the magazine. The forward portion of the card rests upon the top edges of the brackets 11, 12, in closely spaced relation with respect to the periphery of the drum 14, so as to be engageable by a radially projecting wiper element 19 of soft rubber, felt or similar friction material carried by the drum. The envelope magazine consists of a second upstanding channel member 20 bridging the forward and downwardly inclined portion of the brackets 11, 12. Inwardly extending plates 21 are secured to the brackets 11, 12, at their top edges and incline downwardly and extend forwardly beyond the channel member 20. The front wall of the channel member 20 is cut away at 20a to provide a discharge orifice 20 through which the envelope passes after being filled, being slid along the plates 21 beneath and past the rubber covered bail 22 which is journaled upon the channel member 20 and is urged by springs 23 to yieldingly retain the foremost envelope in the magazine until the letter or card has been completely inserted. A chute for guiding filled envelopes during discharge from the magazine is constituted by an angular strip 24 secured to each bracket 11, 12, and a downwardly inclined guide member 25 of wire stock secured at its upper ends to the magazine 20 directs the filled envelopes into the receptacle constituted by a portion of the base 10 and upstanding plates 26, 27, secured thereto.

The mechanism by which the folded letters or cards in the magazine 17 are transferred, one by one, into envelopes placed in the magazine 20 consists of parts carried by or actuated by the drum 14, and guiding and restraining means mounted on the brackets 11, 12. More particularly, and with reference to Fig. 3 of the drawings, the drum 14 is provided with a hooked plate 28 of resilient metal which plate is normally spaced, at its rear or hooked end, from the drum surface, so as to engage the foremost letter in the magazine 17 when caused to drop past the ledges 18 by the forward wiping action of the preceding friction element 19. A rubber covered letter detent or bail 29 prevents the wiper element 19 from carrying the foremost letter or card materially beyond a position in which its rear edge clears the ledges 18 and also serves to hold the card or letter snugly upon the drum surface as it is being carried forward by the hooked plate 28. The letter or card is also held down upon the drum by the wire member 30 which extends upwardly from the brackets 11, 12, downwardly into proximity with the drum surface and forwardly to provide a tongue, shown in Fig. 2, which holds the flap 31a of the foremost envelope 31 in appropriately elevated position. Upon the top edge of each of the brackets 11, 12, is pivotally mounted a combined envelope-spreader and letter guide 32. This element is clearly shown in Figs. 2, 3, 6 and 7 and has the form of a channel slightly belled at its entrance end and beveled at its forward, or envelope-adjacent end. A small coil spring 33 anchored upon a lug 34 on each bracket 11, 12, normally urges the member 32 to assume an inwardly toed position, upon its pivot screw 35, in which position the beveled nose of the member is not inserted within the envelope. The periphery of the drum, adjacent its lateral edges is recessed, as shown by the dotted lines in Fig. 6, to constitute a cam 36 upon which the roller 37 of each mem-

ber 32 contacts, appropriately swinging the member 32 upon its pivot 35 into and out of envelope-engaging and spreading position in timed relation with the feeding of letters or circulars.

From the foregoing description of the machine, its mode of operation may be readily understood. A stack of envelopes 31, flaps unfolded, are placed in the magazine 20 and a stack of folded letters or cards 38 are placed in the magazine 17. The foremost envelope rests with its flap 31a supported upon the tongue of the member 30 and the foremost letter rests with its rear edge supported by the ledges 18. Upon rotation of the drum the friction member 19 thereof, which projects slightly beyond the drum periphery, wipes upon the under surface of the foremost letter 38 and causes it to be moved forward until its front edge contacts the member 29 and its rear edge clears and falls from the ledges 18. Thereupon, the hooked member 28 comes into engagement with the rear edge of the letter 38 as shown in Fig. 3, and the latter is forced beneath the member 29 and is carried toward the waiting envelope which, in turn, has been entered by the envelope-spreader and letter guides 32, due to the action of cams 36 upon the rollers 37 of the members 32. The moving letter then enters the guides 32 and is carried into inserted relation with the envelope 31 and, being continued in its travel by the hooked member 28, causes the filled envelope to be carried from the magazine, through the opening 20a and chute-constituting members 24 into the receptacle formed by the base 10 and walls 26, 27. In the case of a twin machine, such as illustrated, in which there are two sets of members 19 and 28, two envelopes are filled during each revolution of the drum. The operation first recited is cyclically repeated, the envelopes and letters settling in their respective magazines and the other parts returning to original position by spring action and by rotation of the drum.

In Figs. 9, 10 and 11, there is shown a mechanism constituting an ancillary or supplemental apparatus adapted for incorporation in the machine disclosed in Figs. 1 to 3 and, by the use of which, the requirement of unfolding the flaps of the envelopes previous to placement in the magazine 20 may be eliminated. This mechanism consists of a finger or hook 40 which underlies the stack of envelopes 31 and is supported upon guides 41 which are inclined at their rear extremities to constitute lifting cams 41a. The rear ends of the hook 40, which is preferably formed of wire stock, are journaled in and supported by upstanding rocker arms 42 pivotally mounted upon the base 10, and a pin 43 is provided at an intermediate point in each leg of the hook 40 and rests upon a respective guide 41. For the purpose of imparting a reciprocatory motion to the hook 40 such as to cause the pins 43 to periodically ride upon the cam surfaces 41a and periodically actuate the hook to unfold the flap 31a of the foremost envelope, double eccentrics or cams 44 are placed on the drum 14 which cams engage pins 45 disposed intermediate each rocker arm 42. A light leaf spring 46 bears against each rocker arm 42 and maintains the rocker arm in contact with the cam 44.

The mode of operation of the flap unfolding mechanism when applied to the machine should be obvious to those skilled in the art from the foregoing description. The cams 44 cause the member 42 to rock backward and forward, imparting a reciprocatory motion to the flap-engaging hook 40 which results in a lifting of the

hook and engaged flap during the retraction of the hook, as shown in Fig. 9. This rearward motion of the hook 40 is timed to take place just after an envelope has been filled and discharged and thereby unfolds the flap just prior to the entry of the envelope-spreading members 32.

It is apparent that the invention is susceptible of embodiment in numerous forms which will appear to those skilled in the art. For example, in lieu of utilizing the peripheral surface of the drum as the conveyor for letters or cards, one may employ a belt carried upon several drums or rollers. Likewise, continuous unidirectional rotation is not an essential of the invention, but, by appropriate retraction of the hook members 28 after one cycle of feeding, the drum might be revolved clockwise and anticlockwise to obtain the same operation of the elements. Moreover, it is obvious that any mechanical or electrical drive might be substituted for manual power. Similarly, it is not an essential requirement of the invention that the magazine be disposed vertically or above the drum, but with appropriate feeding, the letters or envelopes may be disposed at any location with respect to the drum. Certain elements of the invention are capable of incorporation in other types of machines to similar advantage. The invention is, therefore, claimed broadly, as indicated by the appended claims.

What is claimed is:

1. An envelope-filling machine comprising a drum adapted to rotate about its axis, means for imparting a rotary motion to said drum, a magazine for pieces of printed matter to be inserted in envelopes, a magazine for envelopes, said magazine for envelopes having its muzzle so arranged with respect to said drum as to dispose the foremost envelope in a plane substantially tangent to the peripheral surface of said drum and open toward said drum surface with one edge of said envelope engaging against said surface, and means upon the periphery of said drum for cyclically engaging a piece of printed matter, carrying said piece of printed matter tangentially with respect to said drum surface and inserting said piece of printed matter in said envelope.

2. An envelope-filling machine comprising a drum adapted to rotate about its axis, means for imparting a rotary motion to said drum, a magazine for pieces of printed matter to be inserted in envelopes, a magazine for envelopes, said magazine for envelopes having its muzzle so arranged with respect to said drum as to dispose the foremost envelope in a plane substantially tangent to the peripheral surface of said drum and open toward said drum surface with one edge of said envelope engaging against said surface, and means upon the periphery of said drum for cyclically engaging a piece of printed matter, carrying said piece of printed matter tangentially with respect to said drum surface, inserting said piece of printed matter in said envelope, and conveying said envelope and its inserted matter clear of the muzzle of said envelope magazine.

3. An envelope-filling machine comprising a drum adapted to rotate about its axis, means for imparting a rotary motion to said drum, a magazine for pieces of printed matter to be inserted in envelopes, a magazine for envelopes, said magazine for envelopes having its muzzle so arranged with respect to said drum as to dispose the foremost envelope with its top or flap edge disposed adjacent said drum and with its open edge disposed toward the magazine for the printed mat-

ter, means for spreading open said envelope to receive printed matter, means rotatable in unison with said drum for actuating said spreading means, and means upon the periphery of said drum for cyclically engaging a piece of printed matter, carrying said piece of printed matter from its magazine and inserting said piece of printed matter into said open-mouthed envelope.

4. An envelope-filling machine comprising a drum adapted to rotate about its axis, means for imparting a rotary motion to said drum, a magazine for pieces of printed matter to be inserted in envelopes, a magazine for envelopes, said magazine for envelopes having its muzzle so arranged with respect to said drum as to dispose the foremost envelope with its top or flap edge disposed adjacent said drum and with its open edge disposed toward the magazine for the printed matter, finger means engaging said foremost envelope and actuated by a cam element rotatively associated with said drum for spreading open said envelope to receive printed matter, and means upon the periphery of said drum for cyclically engaging a piece of printed matter, carrying said piece of printed matter from its magazine, inserting said piece of printed matter into said open-mouthed envelope and conveying said envelope and its inserted matter clear of the muzzle of said envelope magazine.

5. An envelope-filling machine comprising a drum adapted to rotate about its axis, means for imparting a rotary motion to said drum, a magazine for pieces of printed matter to be inserted in envelopes, a magazine for envelopes, said magazine for envelopes having its muzzle so arranged with respect to said drum as to dispose the foremost envelope in a plane substantially tangent to the peripheral surface of said drum with its top or flap edge disposed adjacent said drum, laterally movable envelope-spreading finger elements at each side of said foremost envelope engageable within the mouth thereof, cams carried by said drum for actuating said finger elements, and means upon the periphery of said drum for cyclically engaging a piece of printed matter, carrying said piece of printed matter tangentially with respect to said drum surface, inserting said printed matter into said open-mouthed envelope and conveying said envelope and its inserted matter clear of the muzzle of said envelope magazine.

6. An envelope-filling machine comprising a drum adapted to rotate about its axis, means for imparting a rotary motion to said drum, a magazine for pieces of printed matter to be inserted in envelopes, a magazine for envelopes, said magazine for envelopes having its muzzle so arranged with respect to said drum as to dispose the foremost envelope in a plane substantially tangent to the peripheral surface of said drum with its top or flap edge disposed adjacent said drum, laterally movable envelope-spreading fingers of channel cross section pivotally disposed at each side of said foremost envelope and engageable within the mouth thereof, cams carried by the ends of said drum adjacent its periphery for actuating said fingers, and means upon the periphery of said drum for cyclically engaging a piece of printed matter, carrying said piece of printed matter tangentially with respect to said drum surface, inserting said piece of printed matter in said envelope and conveying said envelope and its inserted matter clear of the muzzle of said envelope magazine.

7. An envelope-filling machine comprising a drum adapted to rotate about its axis, means for

- imparting a rotary motion to said drum, a magazine for pieces of printed matter to be inserted in envelopes, a magazine for envelopes having its muzzle so arranged with respect to said drum as to dispose the foremost envelope contained therein in a plane substantially tangent to the peripheral surface of said drum, means operable by the drum for opening said foremost envelope, and a hook carried upon the peripheral surface of said drum, engageable with the foremost piece of printed matter in said first-mentioned magazine and caused, by rotation of said drum, to transfer said piece of printed matter from its magazine to said foremost envelope when opened.
8. An envelope-filling machine comprising a drum adapted to rotate about its axis, means for imparting a rotary motion to said drum, a magazine for pieces of printed matter to be inserted in envelopes, said magazine being disposed with its muzzle facing the peripheral surface of said drum, a ledge within said muzzle for retaining said printed matter in said magazine, a wiping element upon the periphery of said drum effective to displace the foremost piece of printed matter from support by said ledge and cause said piece of printed matter to rest adjacent said drum, a magazine for envelopes having its muzzle so arranged with respect to said drum as to dispose the foremost envelope contained therein in a plane substantially tangent to the peripheral surface of said drum, means for holding said envelope open for reception of printed matter, and a hook carried by said drum to the rear of said wiping element, engageable with the rear edge of said displaced printed matter and caused by rotation of said drum, to drive said piece of printed matter into said opened envelope.
9. An envelope filling machine comprising an endless traveling surface, a magazine for envelopes, a magazine for pieces of printed matter, the discharge of said envelope magazine being so arranged that envelopes discharged therefrom will be positioned with their open edge partially supported on said surface and disposed toward the other magazine, and means carried on said endless traveling surface for removing pieces of printed matter from their magazine and inserting them in said envelopes, said last mentioned means supporting the pieces of printed matter while in transit from their magazine until inserted in an envelope.
10. An envelope filling machine comprising an endless traveling surface a portion of which traverses an arcuate path, an envelope magazine, a second magazine for pieces of printed matter, means for opening the envelopes as discharged from their magazine, and means mounted on said surface and movable with said surface for removing pieces of printed matter from their magazine and inserting them in the envelopes, said last-mentioned means supporting the pieces of printed matter in a plane tangent to the arcuate path of said surface.
